UNITED STATES PATENT OFFICE.

PAUL HAYS, OF LOS ANGELES, CALIFORNIA.

ERASING DEVICE OR BOARD.

1,281,365.

Specification of Letters Patent. Patented Oct. 15, 1918.

Application filed December 27, 1916. Serial No. 139,180.

To all whom it may concern:

Be it known that I, PAUL HAYS, a citizen of the United States, residing at Los Angeles, in the county of Los Angeles and State 5 of California, have invented certain new and useful Improvements in Erasing Devices or Boards, of which the following is a specification.

My invention relates to erasing devices 10 and has particular reference to an erasing board which will enable a typist to make erasures quickly and accurately and without mutilating the paper.

It is well known that much of the erasing 15 necessary in typewriting can be done more easily, quicker and better out of the machine than in. Errors discovered in proof-reading after the paper has been removed from the machine, and mistakes occurring near 20 the bottom of the page are usually erased outside the machine.

The object of my invention is to provide 25 an appliance by means of which erasures may be made in both single and double-space work without injury to adjacent writing.

Another object is to provide an erasing device of the above description on which the sheets to be altered may be rapidly moved into erasing position without picking up 30 each sheet.

The above and other objects of the invention will be apparent from the following description taken in connection with the drawing, in which similar reference characters 35 indicate the same parts in the several figures of the drawing. The invention consists of structural characteristics and arrangements of elements which will be hereinafter more fully described and particularly pointed out 40 in the appended claims.

In the drawings—

Figure 1 is a longitudinal sectional view 45 of an erasing board embodying my invention, the section being taken on the line 1—1 in Fig. 2.

Fig. 2 is a plan view of the erasing board,

Fig. 3 is a sectional view of another erasing board embodying my invention, and

Figs. 4, 5, 6 and 7 are side views of other 50 forms of erasing devices embodying my invention.

The form shown in Figs. 1 and 2 consists of a base member B made of sheet metal. The base has a bottom part 10, and an upwardly inclined guiding surface 11 extends 55 upwardly from the front end of the bottom 10

and is supported at the upper rear end by a downwardly bent part 12. At the rear end of the bottom 10 there is an upwardly and inwardly inclined part 13, the inner end 60 of which is supported by a downwardly bent part 14. The side members 15 close the openings at the sides of the base, and with the walls 12 and 14 form a compartment 16.

The compartment 16 is open at the top 65 and the paper-supporting or erasing block 17 fits into the same. The member 17 may be a hollow or solid elongated block of hard wood, metal, glass, rubber or other suitable material substantially triangular in shape. 70 The ends of a bail 18 engage in openings in the axis of and at the ends of the block 17 and rotatably support the block so that it can be turned about its axis to adjust it to the position desired. The bail 18 passes 75 through openings 19 at the end of the wall 14 and behind the latter thereby pivotally securing the block to the base B. The openings 19 extend the height of the wall 14 so that the block may be raised out of the compartment 16 to turn it.

The block 17 has three parallel convex paper-supporting edges 20, 21 and 22 at the points corresponding to the apexes thereof. Each edge is of different curvature from the 85 others. In general there is only need for two edges, the edge 20 being made of relatively sharp curvature for erasures in single-space work and the edge 21 being of somewhat greater curvature for erasures in 90 double-space work. It is necessary to have edges for both double- and single-space work because the smaller and sharper surface often slightly marks the paper when held over it, while the double-space, being larger, 95 does not and is easier to work on where the adjacent writing is not too close to the erasure.

The third edge 22 may also be used for erasing or may be used as a cover to protect 100 the other two edges when they are not in use.

Part of the edge 22 also forms one of the feet which support the block 17.

In Figs. 1 and 2 a part of the edge 21, and in Fig. 3 a part of the edge 20 provide the 105 other foot upon which the block rests. These feet provide means for rigidly supporting the block while it is in use, keeping it level and preventing it from turning.

Concave faces 23, 24 and 25 are formed in 110 the sides of the block 17 between the convex paper supporting faces so that the paper will

extend downwardly abruptly on both sides of the part on which the erasure is to be made. By lowering the lines on opposite sides of the line or part to be erased those lines cannot be injured by the erasing instrument and on account of the more pronounced elevation given the part to be erased, the erasure may be more quickly and accurately done.

- 10 A concave face will always be disposed opposite the upper end of the inclined surface 11, and constitutes in effect a continuation of the latter. The surface 11 and concave face adjacent or opposite it serves as a 15 means for guiding sheets of paper S from a pile upwardly onto the top of the erasing surface which is uppermost, as is shown in Fig. 1. By placing a pile of sheets requiring erasures on the lower end of the inclined 20 surface 11 or only partly on it, these sheets may be slid one at a time up into position on the block 17 to make erasures. This makes it unnecessary to pick up each sheet and place it on the block and saves considerable time. The concave surfaces on the 25 block 17 keep the sheets from catching under the block.

In Fig. 3 I have shown an erasing device similar to the one shown in Figs. 1 and 2 30 except that in this form a metal guiding member 26 is inserted between the upper end of the inclined surface 11 and the adjacent concave face on the block 17. This guiding member 26 has a concave face which joins 35 the upper end of the surface 11 and the adjacent surface on the block 17 and forms a more accurate guiding device. Instead of a bail 18 I have shown links 27 pivoted to the block 17 and base B respectively.

- 40 In Fig. 4 I have illustrated a form of my invention in which the entire device is made in one piece, or in which the upper surface is made continuous. Here the inclined surface 111 leads upwardly to a concave surface 231 45 which guides the sheet upwardly onto the top of the erasing surface 211. The principle of operation is the same as in the forms already described.

The erasing device shown in Fig. 5 some- 50 what resembles the one shown in Fig. 4 except that in this form I have provided two erasing surfaces spaced apart, the surface 201 being for single-space work and the surface 212 being for double-space work. The 55 inclined surface 112 and concave surface 232 are continuous and serve to guide the paper onto either of the erasing edges. In this form it is not necessary to make adjustments of a separate block to bring the desired surface 60 into position for use.

Fig. 6 represents a similar construction as that shown in Fig. 4, except that it is provided with a tail piece 114 which prevents the board from tilting backward.

65 Fig. 7 represents a construction similar to

Fig. 6, except that the erasing surfaces 213 and 214 are composed of portions of the circumferences of two circles, the surface 213 used for double-space and surface 214 for single-space erasing.

70

When the sheet S has been slid into erasing position as shown in dotted lines in Figs. 1 and 2, it may be gripped on opposite sides of the ridges so as to hold it firmly on the surface with the part to be erased at the 75 apex. To limit the amount erased along the ridge, a card C may be employed, as shown in dotted line in Fig. 2.

The device is inexpensive, easy to handle and by its use much of the dirt which is ordinarily brushed into the typewriting machine will be kept out of the machine and save wear on the machine.

From the foregoing it will be apparent that the invention may be carried out in a 85 number of different ways and accordingly I do not wish to be limited to the exact details shown and described.

What I claim is:—

1. As a new article of manufacture, an 90 erasing device consisting of a firm base section having an upwardly inclined guiding surface adapted to support a sheet of paper and an outer convex paper-supporting edge adjacent to said guiding surface and of such 95 a curvature as to merge into and form an upwardly turned extension of the highest portion of said inclined guiding surface, whereby a sheet or sheets of paper resting on said guiding surface may be quickly and 100 readily transferred on and be made to extend downwardly abruptly on both sides of said supporting edge and raise the part of the sheet of paper on which the erasure is to be made distinctly above the adjacent 105 writing.

2. As a new article of manufacture, an erasing device consisting of a firm base section having a surface adapted to support a sheet of paper and an outer convex paper-supporting edge adjacent to said surface and of such a curvature as to merge into and form an extension of the portion of 110 said surface contiguous to the convex paper supporting edge, whereby a sheet or sheets 115 or paper resting on said surface may be quickly and readily transferred on and be made to extend downwardly abruptly on both sides of said supporting edge and raise the part of the sheet of paper on which the 120 erasure is to be made distinctly above the adjacent writing.

3. As a new article of manufacture, an erasing device consisting of an extended firm base section having an inclined guiding surface adapted to support a sheet of paper and a convex paper-supporting edge adjacent to the highest portion of said guiding surface and of such a curvature as to merge into and form a concave extension of 125 130

- the highest portion of said inclined guiding surface, whereby a sheet or sheets of paper resting on said guiding surface may be quickly and readily transferred on and be 5 made to extend downwardly abruptly on both sides of said supporting edge and raise the part of the sheet of paper on which the erasure is to be made distinctly above the adjacent writing.
- 10 4. An erasing device consisting of an elongated body substantially triangular in transverse cross-section, the edges at the apexes of the triangle being convex to provide three curved paper supporting surfaces, 15 the triangular shape of the device being such that when any one edge is in use the device will be rigidly supported on a base formed between the other two edges.
5. An erasing device comprising an upwardly inclined surface, a member located opposite the upper end of said inclined surface having a plurality of convex paper supporting edges, each of said edges being adjustable to a position above and parallel to 25 said inclined surface, the surfaces of said member which are adjustable opposite the upper end of said inclined surface being concave and forming continuations of said inclined surface to guide sheets from the latter onto the top side of the upper convex 30 edge.
6. An erasing device comprising a base having an upwardly inclined surface and a substantially triangular member carried by the base opposite the upper end of said inclined surface, said triangular member having a plurality of convex paper-supporting and erasing surfaces of different diameters, said member being adjustable about its axis to move either of its convex erasing surfaces 35 above said inclined surface and into position to receive a sheet of paper thereon from said inclined surface.
7. An erasing device comprising a base having an upwardly inclined surface and a compartment at the upper end of said inclined surface, an elongated substantially triangular member fitting in said compartment, means for rotatably mounting said member and pivotally securing it to said 40 base, said member having parallel convex paper-supporting edges and also having concave surfaces adjacent and parallel to said convex edges, said member being adjustable about its axis to bring any paper-supporting edge uppermost and above said inclined edge, said concave surfaces being adapted to form continuations of the inclined surface and guide sheets upwardly 45 onto the uppermost paper-supporting edges. 55

In testimony whereof I affix my signature.
PAUL HAYS.
